[57] CLAIM

The ornamental design for a firebox intake hood, as shown.

DESCRIPTION

FIG. 1 is a left front perspective view of a firebox intake hood, showing my new design;
FIG. 2 is a front elevational view;
FIG. 3 is a side elevational view, the opposite side being substantially a mirror image thereof;
FIG. 4 is a rear elevational view, showing the rodent-proof screen;
FIG. 5 is a top plan view;
FIG. 6 is a bottom plan view; and,
FIG. 7 is a median vertical sectional view, taken on the line 7—7 in FIG. 5.
